UNITED STATES PATENT OFFICE.

STEWART CLARK COEY, OF YOUNGSTOWN, OHIO, ASSIGNOR TO THE YOUNGSTOWN SHEET AND TUBE COMPANY, OF YOUNGSTOWN, OHIO, A CORPORATION OF OHIO.

SKELP-CHARGING APPARATUS.

1,130,708.

Specification of Letters Patent. Patented Mar. 9, 1915.

Application filed January 16, 1914, Serial No. 812,411. Renewed January 15, 1915. Serial No. 2,474.

To all whom it may concern:

Be it known that I, STEWART C. COEY, a citizen of the United States, residing at Youngstown, in the county of Mahoning 5 and State of Ohio, have invented new and useful Improvements in Skelp-Charging Apparatus, of which the following is a specification.

My invention relates specifically to machines for charging skelp into heating furnaces preparatory to welding the skelp into tubes, or to bending the same into other products; but my invention may be used for various other purposes.

15 The objects of this invention are to provide a rapid, simple and positive means for conveying skelp or other blanks of a magnetic or magnetizable nature by the use of a magnet carried by a suitable frame-work 20 or table.

Referring to the accompanying drawings, Figure 1 is a longitudinal vertical section through the shaft on which the conveying magnet is mounted; Fig. 2, an end elevation 25 of a structure embodying my invention, parts being broken away; Fig. 3, a plan of the same, parts being broken away; and Fig. 4, an elevation showing the end opposite that shown on Fig. 2, a portion of the 30 furnace being shown in section.

On the drawings, 1 represents a pair of rails on which the wheels 2 of the charging table 3 travel.

4 is a portion of a heating furnace across 35 one end of which the table 3 may travel back and forth. The top of the table has two levels, the upper or storage level 5 being the one on which the skelp 6 is piled preparatory to being transferred to the lower 40 level. The skelp on the upper level lie parallel to the direction in which they are to be charged into the furnace. They are moved laterally by workmen or by any suitable means so as to cause them to reach 45 their proper position on the lower level now to be described. The said lower level which may be at any desired distance below the upper level is shown parallel to the same. It has the conveying trough or channel 7 50 open upwardly, there being in the bottom of the channel a number of transverse rollers 8 on which the skelp travel with but little friction during the charging operation in order to lighten the work of the charging 55 magnet.

At the end of the charging channel or bed 7 I place one or more rotary chargers 9, having its axis of rotation transversely of the direction in which the skelp is to be charged. The charger preferably projects 60 slightly above the bottom of the channel 7, and is driven by the motor 10 carried by the table and connected to the charger by the belt 11 or other transmission device, so as to cause the top of the magnet to rotate toward the furnace 4. The charger 9 is a horizontal cylinder composed of the two hollow end members or caps 12 composed of magnetizable material and an intermediate member 13 composed of non-magnetizable 70 material, such as brass. The members 12 have their opposing or adjacent ends each provided with a cavity or hollow 14 concentric with the axis of the charger so that the shell or annular wall 15 shall be of uniform thickness. The adjacent ends of the shells 15 are separated slightly to form the annular gap 16 in the magnetic circuit to be described presently. This gap is made wider near the interior surface of the shells 80 by forming the interior shoulders 17 in the shells. The members 12 are connected together by the brass connector 18 which has its ends in the hollows 14 and the central portion of its periphery in the annular 85 space between the ends of the shells 15.

The ends of the charger 9 are supported by the aligned shafts 18 and 19 composed of magnetic material and having their axes in line with the axis of the charger. The 90 opposing ends of these shafts extend through central openings in the ends of the members 12 and into the ends of the member 13 but are separated by a wide gap. The shafts are keyed to the members 12 and 95 13, as shown in Fig. 1.

The shafts 18 and 19 turn in the vertical bearings 20 and 21, respectively, supported by the table, and composed of magnetizable material. The lower ends of the bearings 100 20 and 21 are connected together by the fixed core 22 of the winding 23. The bearings 20 and 21 constitute the end members of a magnetic frame, its magnetic circuit including the core 22, the end members or 105 bearings 20 and 21, the shafts 18 and 19, and the members 12. This circuit is open at the annular gap 16 across which the flux flows when the winding 23 is energized, that is, supplied with an electric current. 110

When the skelp is taken from the charging level 5 and placed in the trough 7 with one end resting on the bodies of the members 12 and bridging the gap 16, the magnetic flux just described as flowing across the said gap is largely diverted so as to travel transversely through the skelp at and about its line of contact with the periphery of the magnet. The rotary charger 9 exerts, therefore, a great tractive or adhesive effect on the skelp and causes it to be charged into the furnace at the surface velocity of the magnet. The electric motor 10 can, as is well known, be controlled so as to give the skelp such initial, final, and intermediate charging speeds as may prove best. After a skelp has been charged into the furnace, the charging table 3 is moved on the rails 1 to the desired position for charging another skelp into the furnace.

My invention dispenses with a large number of men required for the hand charging of skelp; eliminates the danger incidental to the present style of chargers; and saves large losses of time and power required by said chargers.

It is obvious that more than one magnetic feeder or charger may be used at selected places along the trough, or near the one shown.

I claim:

1. The combination of a charging table, a rotary charging roller carried by the table and having a magnetizable periphery relatively to the table, a magnetic circuit energized by the winding and including the said charging roller, the latter being arranged externally of the winding, and means for rotating the roller.

2. The combination of a table, a magnetizable roller having an annular gap, a winding stationary relatively thereto, a magnetic circuit energized by the said winding and including the said roller, the roller being arranged with the said gap transverse of the flux through the roller, and means for rotating the roller.

3. The combination of a table, a trough thereon, a magnetizable roller supported by the table and having its axis of rotation transverse of the trough and its periphery

arranged to be engaged by magnetizable material in the trough, a winding stationary with respect to the table, and a magnetic circuit energized by the winding and including the roller arranged lengthwise therein.

4. The combination of a table, a trough thereon, a magnetizable roller supported by the table and having its axis of rotation transverse of the trough and its periphery arranged to be engaged by magnetizable material in the trough, a winding stationary with respect to the table, and a magnetic circuit energized by the winding and including the roller arranged lengthwise therein, there being a peripheral gap in the roller.

5. The combination of a table, a feed roller having opposite axially-aligned shells of magnetizable material separated by a peripheral gap, non-magnetizable material connecting the shells, means for rotating the roller, a magnetic circuit including the roller arranged lengthwise therein, and a winding stationary with respect to the roller for energizing the said circuit.

6. The combination of a table, a magnetizable roller having an annular gap, a winding stationary relatively to the table, a magnetic circuit energized by the winding and including a fixed core in the winding and the said roller, the gap in the roller being transverse of the flux through the roller, and means for rotating the roller.

7. The combination of a table, a feed roller thereon, a stationary winding, a magnetic circuit, including a core in the winding, arranged to transmit lines of magnetic force through the roller and into magnetizable material on the roller.

8. The combination of a table, a rotatable cylinder supported by the table and having its axis of rotation transverse of the table and its periphery arranged to be engaged by the magnetizable material, a winding stationary with respect to the table, and a magnetic circuit energized by the winding and including the cylinder.

Signed at Youngstown, Ohio, this 10th day of January, A. D. 1914.

STEWART CLARK COEY.
